UNITED STATES PATENT OFFICE.

RALPH E. RICH, OF CHICAGO, ILLINOIS.

PISTON FOR INTERNAL-COMBUSTION ENGINES.

1,248,162.

Specification of Letters Patent. Patented Nov. 27, 1917.

Application filed January 20, 1916. Serial No. 73,148.

To all whom it may concern:

Be it known that I, RALPH E. RICH, a citizen of the United States, residing at Chicago, in the county of Cook and State of Illinois, have invented certain new and useful Improvements in Pistons for Internal-Combustion Engines, of which the following is a specification.

My invention relates to the formation of the piston heads such as are used in internal combustion engines, as for instance, motors for automobiles, motor boats and the like, and has for its object the provision of a radiating and reinforcing structure which shall provide a large amount of radiating surface upon the head wall of the piston, and particularly shall provide for expansion and contraction of the piston uniformly, whereby more or less rapid distortion, and consequent irregular and unequal wear and deterioration are avoided, and which at the same time shall add strength and rigidity to the piston head. It is already well known to those familiar with such engines, that in some respects certain alloys of aluminum are particularly suitable for the construction of pistons, and because of the great conductivity of aluminum and its alloys, and the consequent rapidity with which they absorb and become permeated with heat, and because of the relatively low temperature at which such materials lose their strength and hardness, it has been proposed and found necessary to provide reinforcements of radiating flanges to dissipate excessive heat and strengthen the piston. In all such pistons heretofore known, however, this reinforcement has been connected to the cylindrical side wall of the piston at one or more points, and because of the high degree of expansion and contraction under extremes of heat and cold exhibited by aluminum and its alloys, a warping or distortion of the piston occurred in a short time and destroyed its usefulness. With the purpose of obviating this defect and realizing incidentally the advantages above mentioned I have devised the new and improved form of piston hereinafter illustrated and described, the essential elements of my invention being pointed out in the appended claims.

In the drawings, Figure 1 illustrates a gas engine cylinder equipped with a preferred form of my improved piston; Fig.

2 is a bottom plan view of the inner side of the piston head—that is, the side from which the side wall of the trunk piston illustrated projects; and Figs. 3, 4, 5, 6 and 7 similar bottom plan views of modified forms of piston in which the radiating and strengthening structures consist of different arrangements of flanges or ribs.

My invention may be applied to explosion engines of various types and forms, in which a reciprocating piston is arranged to travel in a cylinder equipped with apparatus for supplying charges of explosive vapor and igniting the same at regular intervals to cause the engine to operate. In the present instance, and for the purpose of illustration, I have shown my invention as applied to a well-known form of automobile engine having a T-head cylinder A, a crank case B of ordinary design, and a trunk piston C, which in the present instance is shown as formed with the usual wrist pin bearings D, providing for its connection to the crank shaft in the ordinary manner, and also as formed with annular grooves arranged to receive the usual packing rings E.

The strengthening and radiating reinforcement of the piston head which constitutes the present invention, comprises, in the preferred form of embodiment shown in Figs. 1 and 2 of the drawing, outer and inner circular flanges or ribs F and G rising from the inner side of the head wall H of the piston concentric with its axis, the outer rib F being entirely free from the side wall I of the piston. Radial cross walls J, in the present instance six in number, extending between the ribs F and G, and three symmetrically arranged radial walls K, meeting each other at the center and extending to points on the rib G intermediate the ends of adjacent walls J, are provided to brace and strengthen the annular flanges F and G, and increase the radiating surface of the reinforcement. From the fact that the reinforcing structure is wholly unattached to the sides of the piston, and also, in some measure, because of the fact that its outer element is circular in form and concentric with the head wall H from which it rises, the stresses arising from the great extremes of temperature to which the piston is subject are symmetrically and uniformly distributed on the piston head and adjacent

portion of its side wall, so that distortion is avoided and the piston remains true in shape and wears uniformly.

It will be understood that while the exact arrangement of the walls of the reinforcing structure in Figs. 1 and 2, and thus far described is particularly well suited to attain the ends in view, this arrangement may be varied within certain limits, the advantages before mentioned being mainly due to the fact that the outer reinforcing rib is entirely free from the side wall of the piston, and to some extent due to the circular concentric arrangement of the outer and inner ribs, and the symmetrical and staggered arrangement of the cross-members. In Figs. 3 to 7, I have illustrated various modified arrangements of the members of the radiating and reinforcing structure which will be understood without extended description. In Fig. 3 the central radial walls are omitted and eight cross walls L connecting the circular ribs M and N are provided. The arrangement shown in Fig. 4 differs from that of Fig. 3 only in that the inner rib is of larger diameter, and a central pin or "stalactite" O is provided to afford an increased central radiating surface. In Fig. 5 which is adapted for a larger piston than those previously described, four central radial walls P are provided, and eight connecting walls Q extending between the outer and inner circular flanges R and S. In Fig. 6, which is adapted for a still larger piston, three circular flanges T, U and V are provided, cross-walls W connecting the flanges T and U, and cross-walls X, arranged in staggered relation to the walls W, connecting the flanges V and V. In Fig. 7, I have shown a system of straight flanges XX and YY which form a central field of cross-ribs, wholly detached from the side-wall of the piston. It is obvious that still other modifications and arrangements are possible without departing from the principles and scope of my invention.

I claim:

1. A piston for explosive engines provided on the inner surface of its head with connected radiating and strengthening members including at least two circular ribs concentric with the axis of the piston, and cross-walls connecting said ribs, the outermost rib being free from the side wall of the piston. 50

2. A piston for explosive engines provided on the inner surface of its head with connected radiating and strengthening members including two circular ribs concentric with the axis of the piston, the outermost wall being free from the side wall of the 60 piston, cross-walls connecting said ribs, and central radial walls extending from the axis of the piston to the inner wall. 55

3. A piston for explosive engines provided on the inner surface of its head with connected radiating and strengthening members including two circular ribs concentric with the axis of the piston, the outermost wall being free from the side wall of the 65 piston, radial cross-walls connecting said 70 ribs, and central radial walls extending from the axis of the piston to the inner wall and arranged in staggered relationship with said cross-walls. 70

4. A piston for explosive engines provided on the inner surface of its head wall with a central field of connected circumferential and cross walls constituting radiating and strengthening ribs and free from the side 75 wall of the piston. 80

5. A piston for explosive engines provided on the inner surface of its head with a central field of connected circumferential and radial walls symmetrically arranged and constituting radiating and strengthening 85 ribs, said walls being free from the side wall of the piston. 85

RALPH E. RICH.
